PERMEABILITY-TUNED COUPLING UNIT

Gus W. Wallin, Chicago, Ill., assignor to Motorola,
Inc., Chicago, Ill., a corporation of Illinois

Application March 6, 1948, Serial No. 13,469

2 Claims. (Cl. 178—44)

1

This invention relates to permeability-tuned coupling units employed in radio sets and the like. A specific example of such a coupling unit is an intermediate-frequency transformer having movable, low-loss iron cores, and the description of the invention contained herein is, for illustrative purposes, particularly directed to a transformer of that type.

A permeability-tuned intermediate-frequency transformer, in common with other intermediate-frequency transformers, includes a coil-and-capacitor assembly mounted in a shield can to prevent stray electromagnetic fields from being picked up by the transformer. As constructed heretofore, such a transformer has included a tubular coil form of molded plastic with a specially built, flat capacitor carried by the base of the form. Iron cores or slugs are mounted in the coil form in such manner that they may be moved axially thereof to vary the inductances of the coils when tuning the transformer to the desired intermediate frequency. The screw adjustments for the slugs customarily have been mounted on the ends of the coil form.

One of the problems attending the use of such transformers has been the difficulty of obtaining the needed coil inductances within rather close space limitations. Thus, there have been practical limits as to the maximum size of shield cans and the minimum size of coil forms and coils in prior constructions. Because of these factors, the shield can of the transformer unavoidably was included in the magnetic field of the coils to an extent where it appreciably affected the coil characteristics. In such instances, the shield can would act in a short-circuited transformer winding, reducing the effective inductances of the coils. To overcome this undesirable effect, it has been proposed to provide the shield can with an inner sleeve or lining of powdered iron to increase the coil inductances and divert most of the magnetic flux from the shield can, thus preventing the can from acting as a short-circuited turn. Such provisions, of course, add substantially to the cost of manufacturing these coupling units.

It is an object of the present invention to provide an improved permeability-tuned intermediate-frequency unit which is of inexpensive construction.

A further object is to provide an intermediate-frequency unit which is of simple construction and which includes a minimum number of parts.

A still further object is to provide an improved capacitor on the base of the coil form.

A feature of the invention consists of replacing the usual molded plastic coil form and tuning

2

slugs respectively with a plastic impregnated, wound paper tube and with tuning slugs which have direct screw-threaded engagement with the tube. The tube has an extremely thin wall so that close coupling is afforded between the slugs and the windings or coils of the transformer. Also, the tube is not required to support the clips which formerly held the adjusting screws. Therefore, both the coils and the slugs may be made quite small in diameter, greatly increasing the space between the coils and the sides of the shield can for a given base diameter. Hence the detrimental influence of the shield can upon the coil inductances is rendered negligible, and the usual powdered iron sleeve can be dispensed with. The paper tube also has the advantage that it is much cheaper to make than the molded plastic form.

Another feature of the invention is the novel capacitor assembly comprising, for example, a flat mica piece silvered on both sides to provide capacitor plates and mounted directly on a ceramic base to which it is secured by the base terminals. This condenser is very low in cost by comparison with the type of capacitor formerly employed.

It has been found that the new unit constructed in accordance with my invention costs considerably less than the existing units available for this purpose, and has equal or better performance.

The foregoing and other objects, features and advantages of the invention will be apparent from a study of the specification taken in connection with the accompanying drawings, in which:

Fig. 1 is a vertical sectional view of an intermediate-frequency transformer constructed in accordance with and embodying the principles of the invention;

Fig. 2 is a cross-section on the line 2—2 in Fig. 1;

Fig. 3 is a longitudinal section through a paper tube coil form which may be employed in the construction shown in Fig. 1;

Fig. 4 is a cross-section on the line 4—4 in Fig. 3;

Fig. 5 is a perspective view of the flat capacitor assembly employed in the transformer of Fig. 1;

Fig. 6 is a plan view of a spring clip used in the transformer of Fig. 1;

Fig. 7 is a longitudinal section through a modified coil form which may be used in lieu of that shown in Fig. 3;

Fig. 8 is a plan view of the coil form shown in Fig. 7;

Fig. 9 is a vertical sectional view of another embodiment of the invention;

Fig. 10 is a cross-section on the line 10—10 in Fig. 9; and

Fig. 11 is a bottom view of the transformer looking from below the chassis on which it is mounted.

In practicing the invention, the stationary coils of an intermediate-frequency transformer are mounted on a thin-walled, small-diameter tubular coil form made of insulating material that is capable of being indented, such as plastic impregnated paper. Screw-threaded tuning slugs are disposed within the coil form, which is indented to cooperate with the threads on the slugs. Flat, fixed capacitors are mounted directly on an annular insulated base which is secured to one end of the coil form. The capacitors comprise a common sheet of dielectric material such as mica which is silvered on both sides to afford condenser plates. The terminals of the unit, which are connected directly to the silver coatings on the mica sheet, serve to secure the capacitors on the base. The coil-and-capacitor assembly is mounted in a shield can and locked into place. Access to the tuning slugs can be had from either end of the coil form by inserting a screw driver therein.

Referring now to the drawings, the embodiment of the invention shown in Figs. 1 and 2 comprises a tubular coil form 12 on which are mounted stationary coils 14 and 16, one of which constitutes the primary winding and the other the secondary winding of the transformer. Tuning slugs or cores of powdered iron or other suitable low-loss magnetic material, indicated respectively by the reference numerals 18 and 20, are associated respectively with the coils 14 and 16. The slugs 18 and 20 are disposed within the tube 12 and are provided with external screw threads. The tube 12, in accordance with the invention, is made of an insulating material which, while thin, can be indented without breaking. A suitable material for this purpose is spirally wound paper impregnated with a plastic composition. The tube 12 is indented to cooperate with the threads of the slugs 18 and 20 so that the same can be positioned longitudinally of the tube 12 by turning them.

One manner in which the tube 12 can be indented to provide a track for the screw threads of the slugs 18 and 20 is illustrated in Figs. 3 and 4. As there shown, transverse notches or indentations 22 are formed in the tube at regularly spaced intervals corresponding to the pitch of the screw threads. Opposite each indentation 22 there is a corresponding internal rib or projection 24 within the tube 12, and the screw threads of the slugs 18 and 20 track in these ribs and the intervening valleys.

In Figs. 7 and 8 there is shown a modified coil form 26 which has longitudinally extending indentations 28 to provide ribs or ridges 30 running lengthwise of the tube 26 interiorly thereof. These ridges 30 preferably are spaced apart about 120 degrees. Being readily deformed, they yield to the threads of the tuning slugs as 18 and 20, Fig. 1, so that the slugs cut their own tracks in the coil form 26.

A disc-like annular base 32, Figs. 1 and 2, is fitted on one end of the coil form 12 and is cemented or otherwise suitably secured thereto. Mounted directly on the base 32 are the fixed capacitors 36 and 38 which are associated with the coils 14 and 16 of the transformer. A sheet or washer 34 of mica or other suitable dielectric material, Fig. 5, has conductive coatings on both sides thereof to afford the plates of the capacitors. Preferably, these coatings are films of silver which are "printed on" the mica washer 34.

Thus, the capacitor 36 has a plate 38 which consists of an arcuate silver coating on the upper side of the washer 34, and a plate 40 consisting of an arcuate coating on the underside of the washer 34. The plates 38 and 40 are arranged so that they are in partially offset relation. Another capacitor 38 comprises plates 42 and 44 on the upper and lower faces of the washer 34, respectively, each of these coatings consisting of an arcuate strip of silver. The plates 42 and 44 likewise are arranged in staggered or partially offset relation.

The soldering terminals of the transformer are mounted on the base 32. These terminals consist of external lugs 46 projecting outwardly from the base 32, and inner lugs 48 to which the leads from the coils 14 and 16 are connected. Each terminal comprises an outer lug 46 and an inner lug 48 connected together by a hollow rivet or eyelet 50 which passes through an aperture in the base 32. This construction enables the capacitors and terminals to be assembled on the base in a single eyeletting operation. Certain of the rivets 50 are in electrical contact with the coatings 38 and 42, while other rivets 50 contact small coating segments 52 which are spaced from the plates 38 and 42 on the upper side of the washer 34 opposite the offset ends of the coatings 40 and 44 on the underside of the washer 34. The rivets 50 which are engaged with the coating segments 52 also have edge contact with the coatings or plates 40 and 44. At the frequencies for which these units are used, there is established a good electrical connection between these terminals and the plates 40 and 44 by virtue of this arrangement. Coating segments 54 are provided on the underside of the washer 34 to correspond with the segments 52 so as to afford uniformity and enable the washer 34 to be used either in the position shown or in an inverted position.

0 position shown or in an inverted position.
The coil and capacitor assembly thus far de-
scribed is adapted to be mounted in a shield can
60, Fig. 1, which is open at its lower end and is
closed at its upper end except for a small aper-
ture through which the coil form or tube 12 pro-
jects. The illustrated shield can 60 is of the type
which is adapted to be secured permanently on
a chassis 62, and the coil-and-capacitor assem-
bly is inserted therein through the opening in
the chassis 62. Mounted on the tube 12 near the
upper end thereof is a spring clip 64, shown in
detail in Fig. 6, having resilient arms 66 that are
adapted to bear against the closed end of the
shield can 60 when the coil-and-capacitor assem-
bly is inserted therein. The base 32 may be of
the twist-lock type shown, for example, in the
copending application of Rudolph A. Becwar,
Serial No. 651,399, filed March 1, 1946, now Pat-
ent No. 2,483,801, issued October 4, 1949. The
spring arms 66 resiliently press the base 32
against the retaining lugs 68 on the chassis 62
when the base 32 is turned to its locked position.
The precise form of the transformer mounting,
however, is merely incidental as far as the present
invention is concerned.

In Figs. 9, 10 and 11 there is disclosed a portable transformer in which the shield can 70 is removable from the chassis 72. The coil form 74 is similar to the coil form 12 of Fig. 1 or the coil form 26 of Fig. 7, except that it is still smaller in diameter and shorter in length. The coils 76 and 78 of the transformer are mounted on the form 74, and tuning slugs 80 and 82 are screw-threaded therein as in the previously-described embodiments. An annular base 84, preferably of ceramic

insulating material, is secured on one end of the coil form 74. The can 70 has a circumferential bead 86 which bears against one side of the chassis 72, and the base 84 has lugs 88 and 90 which extend through recesses in the end portion of the shield can 70 and bear against the other side of the chassis 72. A retaining clip 92, Fig. 11, extends across the underside of the base 84 and is received in apertured lugs 94 on the end of the shield can 70 to lock the entire transformer assembly in position on the chassis 72.

The base 84 (as in the embodiment of Fig. 1) carries a pair of flat, fixed capacitors which are electrically connected to the coils 76 and 80. Arcuate silver coatings such as 96 and 98, Fig. 10, on both sides of a mica washer 100 are electrically connected to hollow rivets or eyelets 102, each of which connects together an outer lug or terminal 106 and an inner lug or terminal 110. The base 84 is recessed to receive the anchor portions of the lugs 106, as indicated at 112, Fig. 11. This prevents the lugs 106 from turning and increases the resistance of the leakage path between terminals. Since the base 84 is not of the twist-lock type, the coil form 74 need not be provided with a spring clip such as 64, Fig. 1, although one may be used if desired.

The tuning slugs 18 and 20 of Fig. 1, or 80 and 82 of Fig. 9 are conveniently adjusted by inserting a screwdriver into either end of the tubular coil form, which guides the tool into engagement with the slugs. The outer ends of the slugs are slotted to receive the blade of the screwdriver.

The invention substantially reduces the costs of the coil form, tuning slugs and shield can by virtue of the new coil assembly. The improved base and capacitor assembly likewise effects substantial savings in cost. Thus, a considerable overall economy results, without any sacrificing of utility and with improved performance in some respects.

While certain specific embodiments have been disclosed herein, these obviously are capable of modification without departing from the spirit of the invention, and it is intended to cover all such modifications in the appended claims.

I claim:

1. A permeability tuned coupling unit adapted to be disposed in a shield can, including in combination, a disc-like insulating base, an elongated coil form secured to said base and extending on one side thereof, at least one coil mounted on said form, capacitor means positioned on said one side of said disc-like base and comprising a dielectric sheet and first and second pairs of conducting coatings thereon, said coatings of each pair being on opposite sides of said sheet and including relatively close spaced portions having capacity therebetween and terminal portions individually offset with respect to each other, said first and second pairs of coatings being offset with respect to each other so that said terminal portions are spaced about said base, and at least two pairs of terminal means securing said dielectric sheet to said base and having portions extending on either side of said base, each of said terminal means

extending adjacent said sheet and engaging a terminal portion of different ones of said conducting coatings to provide electrical connection therewith, said terminal portions extending on said one side of said base forming means for interconnecting said coil and said capacitor means, and said terminal portions extending on the other side of said base forming means for making electrical connections to said coupling unit.

2. A permeability tuned coupling unit adapted to be disposed in a shield can, including in combination, a disc-like insulating base, an elongated tubular coil form secured to said base and extending on one side thereof, first and second coils mounted on said form, first and second magnetic cores supported within said coil form and individually movable with respect to said coils, capacitor means positioned on said one side of said disc-like base and comprising a mica sheet and first and second pairs of conducting silver coatings thereon, said coatings of each pair being on opposite sides of said sheet and being partially offset with respect to each other so that each pair includes relatively close spaced portions having capacity therebetween and terminal portions individually offset with respect to each other, said first and second pairs of coatings being offset with respect to each other so that said terminal portions are spaced about said base, at least two pairs of terminal means securing said sheet to said base and having portions extending on either side of said base, each pair of said terminal means extending through said sheet and individually engaging the terminal portions of one pair of said conducting coatings to provide electrical connection therewith, and means connecting said portions extending on said one side of said base of each pair of said terminal means to one of said coils, said terminal portions extending on the other side of said base forming means for making electrical connections to said coupling unit.
